UNITED STATES PATENT OFFICE

99,975

DESIGN FOR AN INSTRUMENT HOUSING

Robert Heller, New York, N. Y., assignor to The Westfield Manufacturing Company, Westfield, Mass., a corporation of Massachusetts

Application April 16, 1936, Serial No. 62,152

Term of patent 14 years

To all whom it may concern:

Be it known that I, Robert Heller, a citizen of the United States, residing at New York, in the county and State of New York, have invented a new, original, and ornamental Design for an Instrument Housing, of which the following is a specification, reference being had to the accompanying drawing, forming a part thereof.

In the drawing—

Fig. 1 is a front view,
Fig. 2 is a top view, and
Fig. 3 is a rear view of an instrument housing showing my new design.

I claim:

The ornamental design for an instrument housing, as shown.

ROBERT HELLER.
